(57) **CLAIM**

The ornamental design for a pistol frame with extended tang, as shown and described.

DESCRIPTION

FIG. 1 is an upper perspective view of a pistol frame with extended tang.

FIG. 2 is a lower perspective view of a pistol frame with extended tang.

FIG. 3 is a rear view of the pistol frame with extended tang as shown in FIG. 1.

FIG. 4 is a front view of the pistol frame with extended tang as shown in FIG. 1.

FIG. 5 is a top view of the pistol frame with extended tang as shown in FIG. 1.

FIG. 6 is a bottom view of the pistol frame with extended tang as shown in FIG. 1.

FIG. 7 is a left view of the pistol frame with extended tang as shown in FIG. 1; and,

FIG. 8 is a right view of the pistol frame with extended tang as shown in FIG. 1.

The broken lines shown in the drawings disclose unclaimed portion of the pistol frame only and form no part of the claimed design.

1 Claim, 8 Drawing Sheets
